INVENTOR

HOLLAND WHEELER

UNITED STATES PATENT OFFICE.

HOLLAND WHEELER, OF LAWRENCE, KANSAS.

INLET AND CATCH-BASIN.

SPECIFICATION forming part of Letters Patent No. 699,269, dated May 6, 1902.

Application filed March 29, 1901. Serial No. 53,429. (No model.)

To all whom it may concern:

Be it known that I, HOLLAND WHEELER, a citizen of the United States, residing at Lawrence, in the county of Douglas and State of 5 Kansas, have invented certain new and useful Improvements in Inlets and Catch-Basins; and I do declare that the following is a clear, full, and exact description of the invention, which will enable others skilled in the art to 10 which it appertains to make and use the same.

My invention relates to improvements in inlets to catch-basins or gullies of sewers or drains and to the form of inlet in which water is taken into the catch-basin through a 15 horizontal grate in the gutter, together with an opening in and through the curb. It is also applicable to the inlets of drains in floors of factories or similar places in which refuse or dirt in connection with water is discharged. 20 The object of my invention is to construct the inlet in such form that it will not retain wastes or be clogged by the same; also, to make the inlet of such form that it may be readily cleaned, opened up for inspection, or 25 adjusted to the proper height and inclination of the gutter.

I attain these purposes by the forms and arrangements of the parts as indicated and illustrated in the accompanying drawings, in 30 which—

Figure 1 is a perspective exterior and sectional view of my invention applied to a street-gutter as it appears viewed from the roadway looking toward the curb. In this figure the inlet and basin are shown as if a portion were removed and is designed to show on the right-hand side a curb-box C', lined with iron and covered with concrete, and on the left-hand side an iron curb-box C, each respectively 35 suited to use with cement curb and stone curb. Fig. 2 is a perspective and sectional view showing the details of my invention, with modifications of form which may be used, viewed from beyond the curb looking toward 40 the roadway.

Similar letters and figures refer to like parts throughout the several views.

The inlet, the construction of its parts, and their purposes are described as follows, reference being made to the drawings, in which 45 A is a horizontal grate in the gutter. B is the basin-box. O is the inlet in basin. C

is the curb-box. C' is a stone or concrete curb-box with an iron lining L. The grate A is supported by its frame a a a upon adjusting-blocks b b b, one of which is shown detached at b', Fig. 1. These blocks rest on notches c c c of variable depths in the upper edge of the box B, and the height or inclination of the grate A may be regulated by the 55 thickness of the blocks b b or by the depth of the notches c c in which they are placed. The grate A is constructed with bars 1 1 1, which are at right angles to the curb C and are formed with supporting partitions or webs 60 2 2 2. They are made to diminish in width as they approach the curb-box C. The intermediate spaces between the bars 1 1 1 form channels 3 3 3, having steep sloping bottoms. They increase in width and depth in the direction of C and present no obstruction to 65 the passage of water or refuse through the grate into the basin-box. These channels are shown in two different forms in Fig. 2. The essential feature in my invention is that they 70 be of a form not to stop refuse and be entirely open throughout their length. The grate A is held in place by the front and sides of the box B and by lugs on B, (one of which is shown at 4,) so as not to be disturbed by traffic on 75 the street; yet it may be easily taken out to open B.

The space beneath A may be used as part of the basin-box or built up with concrete to be made a part of the foundation of B. The 80 curb-box C (shown in Fig. 1) has a recess D in its end, which receives the end of the curb (shown at C' in Fig. 2) and secures it in proper position.

The curb-box C', (shown in Fig. 1,) which 85 forms a part of the inlet of my invention as adapted more particularly to artificial or concrete curbs, is formed with an interior lining L of suitable form, which supports the exterior curb C' of concrete or artificial stone. 90

I am aware that prior to my invention catch-basin inlets have been made with openings in the gutter which, in connection with an opening in the curb, discharged into the catch-basin; but such inlets usually have 105 cross-bars which form holes in the gutter, which are easily obstructed with refuse. They have also often flat surfaces which retain deposits within the inlet.

Having described the construction and operation of my device, what I do claim as my invention, and desire to secure by Letters Patent, is—

- 5 1. The combination with a curb having an opening in its front and an opening in its bottom, of an open-ended grate having its bars projecting into the front opening, partitions supporting said bars and arranged to form 10 between them channels having sloping bottoms, substantially as and for the purpose described.
2. In a catch-basin inlet, an open-ended

grate having a supporting-frame, a basin-box arranged to support the frame having in its 15 upper edge notches of different depths, and adjusting-blocks adapted for insertion in the said notches, substantially as and for the purpose described.

In testimony whereof I have signed my 20 name to this specification in the presence of two subscribing witnesses.

HOLLAND WHEELER.
